UNITED STATES PATENT OFFICE

2,426,131

TOY ELECTRICAL ENGINE

David J. Weirich, Williamstown, N. J.

Application August 22, 1945, Serial No. 612,079

1 Claim. (Cl. 172—126)

1

The present invention relates to new and useful improvements in toy electric engines, and has for its primary object to provide a device of this character constructed to simulate a V-type internal combustion engine such as provided as the power plant for automobiles and other purposes.

An important object of the present invention is to provide a toy electric engine of this character including a pair of electromagnets arranged in V formation and operated by any suitable source of current and including armatures operated by the electromagnets for driving a crankshaft and to which various types of toys may be operatively connected.

A further object of the invention is to provide means for alternately energizing the electromagnets to deliver power strokes to the crankshaft in a manner to provide for the continuous rotation thereof, together with means for reversing the direction of rotation of the crankshaft, as well as for regulating the speed thereof.

A further object of the invention is to provide a device of this character of simple and practical construction, which is efficient and reliable in operation, relatively inexpensive to manufacture, neat and attractive in appearance and otherwise well adapted for the purposes for which the same is intended.

Other objects and advantages reside in the details of construction and operation, as more fully hereinafter described and claimed, reference being had to the accompanying drawings forming part hereof, wherein like numerals refer to like parts throughout, and in which:

Figure 1 is a side elevational view.

Figure 2 is a top plan view.

Figure 3 is a front elevational view.

Figure 4 is a perspective view of the sliding brushes for regulating the speed and reversing the crankshaft.

Figure 5 is a perspective view of the crankshaft.

Referring now to the drawings in detail, wherein for the purpose of illustration I have disclosed a preferred embodiment of the invention, the numeral 5 designates a metal base and to which a pair of upwardly extending, spaced-apart bearing brackets 6 are attached in which a crankshaft 7 is journaled and provided with a pair of cranks 8 and 9 arranged substantially at an angle of 90° with respect to each other. To each end of the crankshaft 7 is secured a flywheel 10 having a pulley 11 attached thereto and to which a belt (not shown) may be attached for operating any suitable toy.

A pair of L-shaped brackets 12 and 13 are also

2

mounted at an inclined angle in substantially V-shaped formation by means of supports 14 of conductive material, and to which electro-magnets 15 and 16 are attached.

- 5 Armatures 17 and 18 are pivotally attached at one end to the upper ends of the brackets 12 and 13, respectively, and extend transversely across the magnets for actuation thereby when the magnets are energized. Connecting rods 19 and 20 10 are pivotally attached at the outer ends of the armatures 17 and 18 respectively, the connecting rods extending downwardly and inwardly for attaching respectively to the cranks 8 and 9 of the crankshaft.
- 15 The brackets 12 and 13 are constructed of soft iron to conduct magnetic force, which completes a magnetic circuit through armatures 17 and 18 and the iron cores of coils 15 and 16.
- 20 Terminals 21 and 22 are attached to the base 5 by means of a bracket 23 and to which circuit wires from a suitable source of current may be attached, the terminals providing an electrical connection for the magnets through a circuit wire 24 and supports 14.
- 25 The electromagnets 15 and 16 are alternately energized by means of a pair of cams 25 and 26 secured to the crankshaft and operable between the spaced-apart upstanding legs of U-shaped brushes 27 and 28, respectively, supported on an insulation sliding block 29.

30 Each end of the block 29 is formed with a slot 30 for slidably receiving a headed screw 31 extending upwardly from the base 5, the screws and slots serving as guides for the sliding movement of the block. The brushes 27 and 28 are connected to the respective electromagnets 15 and 16 by means of the circuit wires 32 and 33.

35 The electric circuit is through terminal 22, bracket 23, base 5, brackets 6, crank shaft 7 then to cams 25 and 26 which contact brushes 27 and 28, then to coils by way of wires 32 and 33 and then back through wire 24 to terminal 21 which is insulated.

40 In the operation of the device, the electromagnets are intermittently and alternately energized by the cams 25 and 26 contacting the respective brushes 27 and 28, whereby to deliver successive power strokes to the crankshaft 7 for rotating the same.

45 The rotation of the crankshaft 7 may be reversed by sliding the brushes 27 and 28 so that the cams will contact opposite sides of the brushes, the cranks 8 and 9 of the crankshaft then being positioned in an opposite direction for receiving the power impulse from the connecting rod.

55 A pair of L-shaped brackets 12 and 13 are also

The speed of the engine may be controlled by moving the brushes relative to the cams to increase or decrease the area of the contacting surface of the cams with the brushes.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having thus described the invention, what I claim is:

A toy electric engine comprising a plurality of electromagnets, an armature pivoted above each magnet for actuation thereby, a crankshaft mounted for rotation between the magnets, connecting rods between the armatures and the

5 crankshaft for transmitting movement of the former to the latter, and circuit making and breaking means for the magnets to alternately energize the same and including cams carried by the crankshaft, and U-shaped brushes having legs positioned at opposite sides of the cams for engagement thereby and a slideable support for the brushes to move the respective legs of the brushes into and out of contacting position with the cams to increase or decrease the contacting area of the cams with the brushes to vary the speed of the engine.

10 15 20 DAVID J. WEIRICH.
